(57) **CLAIM**

The ornamental design for an automatic locking differential, as shown and described.

DESCRIPTION

FIG. 1 is a left side elevational view of an automatic locking differential the right side being identical;
 FIG. 2 is a top plan view of the automatic locking differential the bottom plan view being identical; and,
 FIG. 3 is an exploded view of the automatic locking differential.

1 Claim, 3 Drawing Sheets(56)
